UNITED STATES PATENT OFFICE.

ROSE M. SHEARER, OF LA PRYOR, TEXAS, ASSIGNOR OF ONE-HALF TO HERMON I. BOWEN, OF LA PRYOR, TEXAS.

PUMP-ROD ELEVATOR.

Application filed October 2, 1924. Serial No. 741,159.

To all whom it may concern:

Be it known that I, ROSE M. SHEARER, a citizen of the United States, residing at La Pryor, in the county of Zavalla and State 5 of Texas, have invented certain new and useful Improvements in a Pump-Rod Elevator, of which the following is a specification.

This invention relates to improvements in 10 elevators for pump rods, casings and the like.

An important object of the invention is to provide a device for raising or lowering 15 pump rods, casings and the like in wells.

15 A further object of the invention is the provision of an elevator which will automatically release the pump rod when the same is forced upwardly.

A still further object of the invention is 20 the provision of an elevating device of this character which may be employed to rotate the pump rod or the like, and separate the same at the joints.

A still further object of the invention is 25 the provision of an elevator of this character which is comparatively simple in construction, very durable and efficient for this purpose.

Other objects and advantages of this in- 30 vention will be apparent during the course of the following description.

In the accompanying drawings forming a 35 part of this specification and in which like numerals are employed to designate like parts throughout the same:

Figure 1 is a perspective view showing 40 my improved device mounted upon a pump rod of a well,

Figure 2 is a side elevation of my im- 45 proved elevator parts being broken away to show the interior construction,

Figure 3 is a front elevation of the same,

Figure 4 is a rear elevation of the same, and

Figure 5 is a transverse sectional view 45 taken on the line 5-5 of Figure 2.

In the drawings, wherein for the purpose of illustration is shown the preferred embodiment of my invention, the numeral 10 50 generally indicates a common form of derrick usually employed in well digging operation. Extending upwardly through the center of the derrick is a pump rod 11 composed of a plurality of sections.

55 Referring more particularly to my im-

proved device, the numeral 12 indicates the main stanchion or beam, the lower portion of the same being substantially rectangular in cross section as indicated at 13 while the upper portion shown at 14 is oval in form. 60 The beam 12 is preferably bent in the form of an arc in order to more evenly distribute the load carried thereby. The lower extremity of the beam 12 is provided with a loop 15, this loop being formed by tapering 65 the lower extremity and rolling the same. The upper extremity of the beam 12 carries a connecting link 16 which is pivotally secured to the beam 12 by means of a pin 17.

A movable jaw member 18 is pivotally 70 connected to the lower portion of the beam 12, the rear portion of the member 18 being provided with a slot 19 permitting insertion of the loop 10 of the beam 12. A pivot pin 20 is secured through the rear portion of the 75 member 18 and loop 15 formed on the beam, permitting rotation of the jaw member 18 in relation to the beam 12. The jaw member comprises a pair of parallel extension bars 21, the forward extremities thereof tapering 80 and being curved downwardly somewhat as shown at 22. A longitudinal slot 23 formed between the extension bars 21 is adapted to receive the pump rod or casing. The rear portion of the movable jaw member 18 is 85 somewhat heavier than the extension bars, thus forming a shoulder 24 near the extremity of the slot 23.

A substantially U-shaped bracket 25 is 90 pivotally connected to the beam 12, the upper extremity of the bracket 25 being provided with openings adapted to receive a pivot pin 26 inserted through a suitable opening in the central portion of the beam 12 and the openings formed in the extreme 95 ends of the bracket 25. The lower portion of the bracket 25 is substantially wider than the upper portion as shown at 26', enabling the bracket to engage the jaw member 18. As shown in Figure 2, the bracket 25 when 100 positioned about the jaw 18 retains the same at substantially right angles to the main beam 12 thereby readily supporting a pump rod or the like.

A trip plate 27 is pivotally mounted in 105 the intermediate portion of the U-shaped bracket 25, this plate being adapted to retain the U-shaped bracket in position during the operation of the elevator and to permit the same to be automatically released up- 110

on upward movement of the pump rod. A bearing pin 28 is positioned through the upper portion of the trip plate while the extremities thereof extend outwardly from the 5 sides of the trip plate and engage suitable openings formed in the U-shaped bracket 25. The lower portion of the trip plate is slightly bent as shown at 29 enabling this extremity to readily engage the shoulder 24 and limit movement of the bracket 25. The upper extremity is also provided with an angular extension 29' forming a guard insuring contact of the trip plate by the sucker rod.

15 It is to be noted that a shoulder 31 is formed near the extremity of the slot 23, this shoulder reducing the width of the slot near the extremity and permitting engagement of a plurality of rods, as, although one shoulder 20 is illustrated in the drawings, it may be readily conceived that a plurality of these shoulders may be formed upon the extension bars 21 to permit engagement of various size rods. The principal purpose of these 25 shoulders is to enable the positioning of the jaw member upon the reduced extension of sucker rods and the like and to engage the same tightly enough to permit rotation of the same for connection or separation of the 30 sections.

In use, my improved elevator is especially adapted to be employed in connection with well digging operations, providing means for elevating or lowering the sucker rod, casings or the like within the well. As 35 clearly illustrated in Figure 1, it is considered advisable to employ two elevating devices of the character described. These elevators are supported by cables or the like 40 connecting with the rotatable links 16, the upper extremity of the cable or the like being mounted upon pulleys and operated by means of motors or the like. One of the elevators is lowered and secured upon the 45 sucker rod. This is accomplished by inserting the extension bars 21 about the reduced neck of the rod immediately beneath the collar, the U-shaped bracket being then positioned about the extension bars and locking 50 the elevators. When it is desired to raise the sucker rod from the well, the elevator is drawn upwardly until the next joint appears 55 above the floor-board, at which time the second elevator is positioned below this joint. The second or lower elevator is positioned 60 about the reduced neck of the second section in an open position as shown in Figure 1, the extension bars 21, forming the jaw member, and engaging the neck portion of the sucker rod and preventing movement of the lower section. One of the elevators is then held stationary while the other is rotated acting as a wrench member and disengaging the upper sucker rod section.

65 After the upper section has been discon-

nected it may be readily released from the elevator by forcing the section upwardly and operating the trip plate causing the U-shaped bracket to become disengaged from the extension bars 21 due to the fact that the 70 trip plate will engage the beam 12 to force the same away from the bracket 25, while the weight of the upper end of the beam and the means for attaching the cable thereto will swing the bracket 25 further away from the lower end of the beam 12 upon further upward movement of the section, thus freeing the section. The lower elevator is then swung over into the locked position as shown in Figure 2, and may be employed to raise 75 the next section, after which the operation is repeated until all the sections comprising the sucker rod have been withdrawn from the well.

These elevators will enable sucker rods 80 and the like to be raised or lowered with great efficiency and in less time than the operation can be accomplished with elevators now commonly employed. It is obvious that this device will effectively prevent 85 accidental displacement of the rod during the operation and will securely retain the rod until the elevators have been released.

It is to be understood that the form of my invention herewith shown and described is 90 to be taken as the preferred example of the same, and that various changes as to the shape, size, and arrangement of parts may be resorted to without departing from the 95 spirit of the invention or the scope of the 100 subjoined claims.

Having thus described my invention, I claim:

1. A device of the character described comprising a main supporting beam, a jaw member pivotally connected to the said beam, a bracket pivoted to the beam member and adapted to retain the jaw member in a horizontal position, and means for automatically releasing the said jaw member.

2. A device of the character described comprising a main supporting beam, a U-shaped jaw member pivotally connected to the lower portion of the said beam, a bracket pivoted to the said beam and adapted to retain the jaw member in a horizontal position, and a trip plate mounted upon the bracket for automatically releasing the same.

3. A device of the character described comprising a main supporting beam, a link member mounted on the upper portion of the said beam, a rod or pipe jaw pivotally mounted on the lower portion of the said beam, a bracket adapted to engage the jaw in a closed position pivoted to the said beam, a trip plate pivotally mounted on the intermediate portion of the bracket, and means for automatically releasing the said pivoted jaw member.

4. An elevator comprising an arcuate sup-

porting beam, a U-shaped jaw pivotally connected to the lower extremity of the said beam, means formed on the inner side of the jaw member for engaging different sized rods, a jaw supporting bracket pivotally connected to the intermediate portion of the beam, a trip plate pivoted to the bracket member and adapted to automatically release the same, and a connecting link member pivotally connected to the upper portion of the said beam.

5. A pump rod elevator comprising an arcuate supporting beam, a loop formed on the lower portion of the said beam, and a connecting link pivotally mounted on the upper extremity of the said beam; a U-shaped jaw member comprising a pair of extension bars, the rear portion of the jaw having a slot adapted to receive the loop formed on the lower portion of the beam, a pivot pin mounted through the said slotted end of the jaw and adapted to engage the loop formed

on the beam, and a shoulder formed on one extremity of the said jaw member; a substantially U-shaped bracket having diverging leg members, the upper portion of the said bracket pivoted to the intermediate portion of the said beam, the lower portion of the bracket being of sufficient width to engage the jaw member when in the horizontal position; and a trip plate having angular bent extremities pivotally mounted upon the intermediate portion of the said U-shaped bracket, the said trip plate being adapted to disengage the bracket from the jaw member upon upward movement of the pump rod carried by the elevator.

In testimony whereof, I have affixed my signature in the presence of two witnesses.

ROSE M. SHEARER.
